SYNCHRONIZING SYSTEM

Hugh C. Ressler, West Brighton, Staten Island,
N. Y., assignor to Radio Inventions, Inc., New
York, N. Y., a corporation of New York

Application November 6, 1939, Serial No. 303,087

10 Claims. (Cl. 178—69.5)

The present invention concerns synchronizing systems and, in particular, a system for synchronizing motor-driven facsimile recorders by means of a substantially pure sine wave signal harmonically related to, and derived from, a series of periodic impulses.

One object of the present invention is to derive a series of periodic impulses from a series of periodic impulses of lower period.

Another object of this invention is to derive a substantially pure sine wave signal from a series of periodic impulses.

Another object is to derive substantially pure sine wave harmonic signals from lower frequency periodic signals by means of aperiodic circuits.

Still another object is to provide highly efficient harmonic signal deriving means by means of inexpensive and practical circuits.

These and other objects of the present invention will be evident from the detailed description of the various figures of the drawings.

In the past, synchronizing impulses have been utilized in a number of ways to control facsimile receiving apparatus. One system is described in the patent entitled "Facsimile synchronizing system" issued March 11, 1941, and bearing No. 2,234,919. In this system, a tuning fork acts to filter a desired frequency component from a received synchronizing impulse and is in turn synchronized by the filtered component. Another system is shown in the copending application entitled "Facsimile synchronizing system" filed on September 14, 1939, and bearing Serial Number 294,868. A system is shown in which the fundamental frequency of the synchronizing impulse is first recaptured and this fundamental frequency is multiplied to produce the desired synchronizing frequency.

In the present system, signals of the desired synchronizing frequency are derived by one or more selective frequency multiplications of the received impulse. The amplitude of signal is limited at one or more points and the selective multiplication is carried on in aperiodic circuits by means of bridge type selective feed-back circuits. By adjusting the selective system in such a way that undesired signal components on either side of the desired component tend to equalize a considerable increase in stability is realized.

In the drawings:

Fig. 1 shows a facsimile receiver circuit embodying one form of the present invention.

Figs. 2, 3, 4, 5, 6, 7, 8 and 9 show various curves and diagrams useful in explaining the operation of the invention.

Fig. 10 shows a block diagram of the components of one form of the invention.

In Fig. 1 is shown one form of the present invention included in a facsimile receiver. The receiver includes a conventional carrier wave receiver 3 connected to antenna 1 and ground 2. Receiver 3 feeds a signal separator 4 which in turn feeds both recording and synchronizing devices. The recording signals after separation are rectified and amplified in the rectifier and amplifier unit 5 and fed to recording stylus 7, in order to record on a record sheet attached to or passing over drum 6. Drum 6 is driven by synchronous motor 8 which receives its power from power amplifier 65. The desired speed relation between motor and drum speeds is secured by means of gear box 8'. Since the components so far described are not directly the subject of this invention, they are shown in block diagram, indicating that alterations or substitutions may be made consistent with the synchronizing system to be described.

The present invention concerns the circuits for transforming synchronizing impulses into desired substantially steady signals. These circuits are shown connected between one output of signal separator 4 and the input to power amplifier 65. In the preferred form shown, these circuits include the limiter-amplifier stage utilizing tube 11, the selective feed-back stage utilizing tube 25, the second limiter-amplifier stage utilizing tube 40 and the second selective feed-back stage utilizing tube 49, which last stage feeds power amplifier 65.

35 Synchronizing impulses from signal separator 4 are applied to grid 13 and diode plate 14 of tube 11 thru the series resistor 10 and across grid leak resistor 9, one end of which is connected to ground. 2. Tube 11 also includes cathode 15 connected 40 to ground 2 and plate 12 energized from plate voltage source 17 thru load resistor 16. The synchronizing signals received from the signal separator 4 are relatively widely separated impulses, such as impulses of $\frac{1}{60}$ second duration 1/3.3 second apart, as shown in Fig. 5. These impulses are limited by the action of diode plate 14 to a predetermined level as shown by the dotted line in Fig. 5, in order to supply essentially constant amplitude impulses to grid 13 in the presence of fading, etc. This leveling takes place due to the fact that when the positive voltage due to the impulses at plate 14 causes plate 14 to draw current, the impedance between plate 14 and cathode 15 becomes very low and any further increase in instantaneous signal is dissipated in resistor 10.

These amplitude limited impulses are amplified by tube 11 and appear across plate load resistor 16. These impulses are made up of a fundamental and a large number of harmonics. A number of the harmonics are represented by the vertical lines *a*, *b*, *c*, *d* and *e* in Fig. 2. The selective feed-back amplifier utilizing tube 25 selects one of these harmonics *c*. Tube 25 includes cathode 24, control grid 26, screen grid 27, suppressor grid 28 and plate 29. Impulses from tube 11 appearing across load resistor 16 are applied to grid 26 from a tap 21 on grid resistor 20, which is coupled to load resistor 16 thru coupling condenser 19. A grid bias battery 22 is connected between grid resistor 20 and cathode 24. Plate 29 is loaded by resistor 30 and energized from plate voltage supply 17. Between plate 29 and grid 26 is connected a selective circuit including resistors 34, 35 and 59 and condensers 32, 33 and 36 connected to ground 2 at the junction between resistor 59 and condenser 36 and to plate 29 thru blocking condenser 31. This selective circuit transmits all frequencies except frequency *f* as determined by the equation

$$f = \frac{1}{6.28} RC$$

where $R = R_{34} = R_{35} = 2(R_{59})$ and

$$C = C_{32} = C_{33} = \frac{1}{2}(C_{36}).$$

At frequency *f* there is no transmission thru the feed-back circuit and the amplifier stage has full gain. At frequencies higher and lower than *f*, there is transmission thru the bridge feed-back circuit and the amplifier gain is reduced rapidly by the degenerative feed-back. Thus tube 25 functions as a selective amplifier and it has been found to be highly selective in spite of the fact that its associated circuits are aperiodic embodying only resistors and condensers. It has been found that if the bridge is balanced at the frequency of desired component *c* of Fig. 2, as shown by selectivity curve *g*, that the resulting components are as shown in Fig. 3 where *m* is the selected desired component and *h*, *k*, *n* and *p* are the attenuated undesired components. It will be noted that the adjacent undesired component *k* is greater than the adjacent undesired component *n* on the other side of *m*, which in practice produces a condition in which component *k* is relatively more troublesome than *n*. If, however, the bridge is balanced to be selective, as shown at *f* of Fig. 2 to one side of *c*, so that undesired components *b* and *d* are made more nearly equal, as shown at *t* and *v* in Fig. 4, the interference due to undesired components is reduced and the stability of the system is increased. This shifting of the selectivity curve toward the smaller amplitude or higher frequency undesired component has also been found to produce greater equality of spacing of the desired harmonic component in time especially near its zero voltage points.

The frequency multiplied synchronizing impulse signals are limited by tube 40 in which diode plate 43 in conjunction with cathode 44 operates to limit signals of more than a predetermined amplitude. When the predetermined amplitude is reached, the signal is limited by series resistor 39 and the limited signal appears on grid 42. The signals resulting from the first multiplication appearing at plate 29 are applied across grid resistor 38 to one end of resistor 39 thru coupling condenser 37. The limited signals applied to grid 42 are amplified by tube 40 and appear on plate 41 and across plate load resistor 75

one end of which is connected to plate battery 17.

A desired range of harmonics of the amplified-limited signals are applied across resistor 48 thru blocking condenser 47. Condenser 47 is made small enough to substantially limit the fundamental components of the plate voltage signals thus increasing the ratio of desired harmonic components to the lower frequency components resulting in signals of the general form shown in Fig. 7.

A portion of these harmonic accentuated signals are applied to the second selective amplifier tube 49 by connecting grid 51 to a tap 48' on resistor 48. Tube 49 includes a cathode 50, control grid 51, screen grid 52, suppressor grid 53 and plate 54. Tube 49 is made to function as a selective amplifier by connecting a selective feed-back circuit between plate 54 and grid 51 comprising resistors 58, 60 and 61 and condensers 55, 57 and 62 coupled to plate 54 thru blocking condenser 55 and grounded at junction of resistor 60 and condenser 62. The circuit is selective at a new harmonic frequency *f'*, the amplifier operating at full gain at this frequency. At frequencies higher and lower than *f'*, the circuit feeds back a degenerative voltage to grid 51, reducing the gain of the stage at these frequencies. As before, the circuit is made to be selective at a slightly higher frequency than the frequency of the desired harmonic component which it is to select in order to minimize the disturbing effect of undesired adjacent harmonics. The finally selected harmonic will have a substantially pure sine wave form. This harmonic is reproduced across plate load resistor 63, energizing plate 54 from battery 17. This desired harmonic is then applied to power amplifier 65, thru blocking condenser 64, where it is amplified and utilized to drive motor 8 connected by leads 66 and 67.

Figs. 5, 6, 7, 8 and 9 show the evolution of the final steady sine wave synchronizing tone of Fig. 9 from the transmitted synchronizing impulse of Fig. 5. As described above, the received synchronizing impulses of Fig. 1 are limited as shown by the dotted line in the limiter tube 11. These impulses may be, for instance, $\frac{1}{60}$ second long separated 1/3.3 second. Selective amplifier 25 generates a 20 cycle damped wave as shown in Fig. 6. When this wave is limited by tube 40 at the dotted line of Fig. 6, the 20 pulses per second shown in Fig. 7 are produced. Equalization of adjacent harmonics insures that the zero crossings of Fig. 6 are equally spaced and hence that the impulses of Fig. 7 will also be evenly spaced. The high frequency components of Fig. 7 passed to tube 49 are shown by Fig. 8. The selective amplifier tube 49 produces a steady 60 cycle tone from the impulses of Fig. 8 as shown in Fig. 9. The stability and equality of zero points of the wave of Fig. 9 is improved by the undesired harmonic equalizing condition described above.

It has been found that this method of selecting a desired harmonic and minimizing the disturbing effect of undesired harmonics permits frequency multiplication steps approximately double those possible with selective circuits tuned exactly to the desired harmonic.

This system has been used and found to be highly stable when the received impulses have a fundamental frequency of $3\frac{1}{3}$ cycles per second, the first selective feed-back amplifier produces 20 cycles and the second produces 60 cycles. Transient effects in the system are almost entirely absent due to the use of aperiodic circuits.

This has been found to be desirable, especially since the received synchronizing signal consists in spaced impulses capable of producing transients in an oscillatory circuit.

While selective amplifiers 25 and 49 have been shown as pentodes, other types of tubes may be used. Also, the limiter tubes 11 and 40 are not limited to triodes. The number of limiter stages and the number of selective stages is not limited to two or to the same number of each. In some cases of frequency multiplication, a single harmonic equalizing selective feed-back stage may be sufficient for deriving a desired harmonic from a number of harmonics.

While one particular system has been shown for carrying out the present invention, many modifications are possible within the spirit and scope of the invention, as set forth in the appended claims.

What is claimed is:

1. In a system for operating a synchronizable motor from a source of signal impulses, the combination of, an amplitude limiting device for equalizing the amplitudes of said signal impulses, an aperiodic selective circuit for selecting a first desired component from said equalized impulses, a second amplitude limiting device for equalizing said selected first desired component, a second aperiodic selective circuit for selecting a second desired component from said last equalized component, an amplifier for amplifying said second selected component, and a circuit for applying said amplified component to said motor to control the speed of said motor in predetermined relation to signal impulses.

2. In a system for operating a synchronizable motor from a source of synchronizing impulses, the combination of, an amplitude limiting device for equalizing the amplitudes of said impulses, an aperiodic selective amplifier for deriving a substantially sinusoidal signal wave of predetermined frequency from said impulses, and an amplifier for amplifying said signal wave sufficiently to operate said motor therefrom.

3. In a system for operating a synchronizable motor from a source of synchronizing impulses, the combination of, an amplitude limiting device for equalizing the amplitudes of said impulses, an aperiodic selective amplifier for deriving a substantially sinusoidal signal wave of a higher frequency from said impulses, and an amplifier for amplifying said signal wave sufficiently to operate said motor therefrom.

4. The method of operating a tunable harmonic selector selecting a desired harmonic from a group of uniformly spaced harmonics in which undesired harmonics adjacent to said desired harmonic are of unequal amplitude for minimizing the effects of undesired harmonics which includes tuning said selector slightly off the desired harmonic in the direction of the lesser of two adjacent undesired harmonics on either side of said desired harmonic.

5. The method of operating a tunable harmonic wave selector selecting a desired harmonic from a group of uniformly spaced harmonics in which said desired harmonic lies midway between two undesired harmonics of unequal amplitude in conjunction with an amplitude limiter which includes tuning said selector slightly off the desired harmonic in the direction of the lesser of said two adjacent harmonics and afterward passing said selected harmonic thru said amplitude limiter.
6. In a system for operating a synchronizable electric motor under control of impulses derived from a source of synchronizing signals, the combination of, a thermionic vacuum tube with a resistor in series with one of its elements for equalizing the amplitudes of said signals, an amplifier including a resistance-capacity feed-back network for controlling the frequency characteristics
- 15 of said amplifier for deriving a signal wave of a frequency adapted to operate said motor, and a second amplifier for amplifying said signal wave sufficiently to operate said motor synchronously therefrom.
- 20 7. In a system for operating a synchronizable motor under speed control of a series of substantially equally spaced impulses, the combination of, a thermionic vacuum tube and associated circuit for deriving constant amplitude unidirectional signals from said impulses, a second thermionic vacuum tube and an associated feed-back circuit for selecting a desired harmonic from said unidirectional signals, a thermionic vacuum tube amplifier for generating sufficient power to operate said motor synchronously with said harmonic, and a circuit for applying said power to said motor.
8. The method of operating a tunable harmonic selector selected a desired harmonic from a group of uniformly spaced harmonics in which the selector is tuned slightly off the desired harmonic to a higher frequency to minimize the effects of the undesired harmonics on the waveform of the selected harmonic.
- 40 9. In a system for operating a synchronizable motor from a source of synchronizing impulses, means for selecting a desired harmonic of said impulses for operating said motor wherein the selecting means has a maximum response at a frequency higher than the frequency of said desired harmonic.
- 45 10. In a system for operating a synchronizable motor from a source of synchronizing impulses made up of a fundamental and a plurality of harmonic components of decreasing magnitude a selective circuit for selecting a desired harmonic from said plurality of harmonics wherein said selective circuit has a maximum response to one side of said desired harmonic in the direction of the lesser of the two harmonics next adjacent to said desired harmonic.

HUGH C. RESSLER.
